(57) **CLAIM**

We claim the ornamental design for a handlebar grip, as shown and described.

DESCRIPTION

FIG. 1 is a perspective view of a handgrip embodying the present invention.

FIG. 2 is a top view of the design shown in FIG. 1.

FIG. 3 is a bottom view of the design shown in FIG. 1.

FIG. 4 is a rear view of the design shown in FIG. 1.

FIG. 5 is a front view of the design shown in FIG. 1.

FIG. 6 is right side view of the design of FIG. 1; and,

FIG. 7 is a left side view of the design of FIG. 1.

The portions of the handlebar grip shown in broken lines form no part of the claimed design.

1 Claim, 4 Drawing Sheets
